[57] CLAIM

The ornamental design for a sport shoe sole, as shown and described.

DESCRIPTION

FIG. 1 is a rear perspective view of the sport shoe sole of the present invention, including phantom lines orienting the sole with an upper portion of a shoe and forming no part of the claimed design;

FIG. 2 is a front perspective view thereof, also including phantom lines orienting the sole with an upper portion of a shoe and forming no part of the claimed design; and

FIG. 3 is a bottom plan view thereof;

FIG. 4 is a front end view thereof with the phantom lines depicting solely environmental structure and forming no portion of the claimed design; and

FIG. 5 is a rear end view thereof with the phantom lines depicting solely environmental structure and forming no part of the claimed design.
